UNITED STATES PATENT OFFICE.

KATHARINE B. HIBBS, OF OAKLAND, CALIFORNIA.

DOLL DRESS.

Application filed May 24, 1920. Serial No. 383,704.

To all whom it may concern:

Be it known that I, KATHARINE B. HIBBS, a citizen of the United States, residing at Oakland, in the county of Alameda and State of California, have invented certain new and useful Improvements in Doll Dresses, of which the following is a specification.

This invention relates to improvements 10 in doll dresses, and particularly to a detachable type adapted to be used in connection with flat paper or cardboard dolls.

The principal object of the invention is to provide a simple and inexpensive device 15 by means of which a child may be readily and inexpensively taught the correct combination of colors and designs in clothing, especially in girls' and women's dresses.

The accompanying drawing illustrates 20 my idea, on which drawing:

Figure 1 is a front view of the dress in position on a doll.

Figure 2 is a sectional view on a line 2—2 of Figure 1.

25 Figure 3 is a fragmentary view of the rear of the dress, showing the means for hanging the same on the doll.

Referring to the numerals of reference on the drawings, 1 denotes a base member or 30 backing, preferably of cardboard or similar material, and shaped to conform closely to the figure of a paper doll 2.

On this base may be pasted or otherwise secured a dress design of any desired pat-

tern, such as is shown at 3, the material used 35 being any scraps of dress fabrics of various colors, such as may be had anywhere. By this means, a child may very quickly be taught the correct color combinations for dresses and also to combine the various 40 scraps to form different designs.

To hang the dress onto a paper doll the base 1 is provided with hooks 4 on the back thereof and near the top, which are adapted to hank over the shoulders of the doll 2. A 45 number of the base members 1 may be provided for a single doll, so that a number of dresses may be put together and the effect compared, or a dress may be pulled off the base and the latter used again, 50

Having thus described my invention, what I claim as new and useful is:

In an educational appliance, a design 55 fashioned in the shape of a doll, a base member constructed of cardboard or some similar material and fashioned in the shape of said doll, L shaped pieces of metal attached to the back of said base member adjacent to the edges of said shoulder portions, a major portion of the length of each piece 60 of metal being parallel to the surface of said base member so that each piece of metal constitutes a downwardly opening hook, said hooks converging downwardly and a dress made up of scraps of cloth of 65 various colors pasted to said base member.

In testimony whereof I affix my signature.

KATHARINE B. HIBBS.
